UNITED STATES PATENT OFFICE.

EDWARD B. WILBUR, OF RAYNHAM, MASSACHUSETTS.

DESIGN FOR A STOVE-COVER LIFTER.

Specification forming part of Design No. 5,294, dated September 26, 1871.

To all whom it may concern:

Be it known that I, EDWARD B. WILBUR, of Raynham, of the county of Bristol, of the State of Massachusetts, have invented or produced a new and ornamental and useful Design for Stove-Cover Lifter; and do hereby declare the same to be fully described in the following specification and represented in the accompanying drawing, of which—

Figures 1 and 2 are opposite side views, and Fig. 3 an edge view of it.

It consists of a head, A, and an open handle, B, arranged and formed as represented. The form of the head is trapezoidal, in top or bottom

view, and bent or angular, as shown in edge view. The handle widens as it recedes from the head, and is semicircular or rounded at its outer end. It is provided with an opening, a, extended through it lengthwise, each branch of the handle being circular in transverse section.

I claim—

The design for a stove-cover lifter, substantially as represented in the drawing, and as hereinbefore described.

EDWARD B. WILBUR.
